UNITED STATES PATENT OFFICE.

HOWARD MARTIN, OF MONMOUTH, ILLINOIS, ASSIGNOR TO A. G. PATTON, OF MONMOUTH, ILLINOIS.

DUMP CAR.

Application filed December 28, 1923. Serial No. 683,114.

To all whom it may concern:

Be it known that I, HOWARD MARTIN, a citizen of the United States, and a resident of the city of Monmouth, in the county of 5 Warren and State of Illinois, have invented certain new and useful Improvements in a Dump Car; and I hereby declare that the following is a full, clear, and exact description of the same, reference being had to the 10 accompanying drawings, and to the numerals of reference marked thereon, which form a part of this specification.

This invention relates to dump cars of that type involving a downwardly swinging 15 bottom door and it is among the objects of this invention to provide control and sustaining mechanism for the door that is durable in use, simple in operation, cheap in construction and maintenance and in which 20 parts may be readily replaced.

The invention comprises the novel structure and combinations herein described and more particularly pointed out and defined in the appended claims.

25 In the accompanying drawings which illustrate a preferred embodiment of this invention and in which similar reference numerals refer to similar features in the different views:

30 Figure 1 is a side elevational view of a dump car embodying this invention.

Figure 2 is a top plan view of the same with parts broken away.

35 Figure 3 is an enlarged fragmentary elevational view of the dump car illustrating the operation of the same.

Figure 4 is a sectional view upon the line 4—4 of Figure 3.

40 Figure 5 is an enlarged sectional view upon the line 5—5 of Figure 3.

As shown on the drawings:

In referring to the drawings which illustrate one embodiment of this invention, there is shown a dump car provided with 45 swing sections or doors 1 in the bottom. Any number of doors may be provided in connection with each car, and as they are all similar only one will be described. Along the central part of the under side of the 50 bottom of the car there extends a center sill or beam or abutment 2 which may consist of channel sections as shown in Figure 4 or any other suitable construction. A pair of U shaped hinge members

3 are rigidly secured to the beam 2 adjacent the bottom door-way. The doors 1 are provided with supporting cleats 4 upon the bottom thereof. These cleats are so spaced and of such dimensions as to fit within the hinge member 3 to which they are pivoted by bolts 5 (Figure 2). They are likewise firmly secured to the bottom of the doors and extend beyond the front end thereof as clearly shown in Figures 4 and 5. A pair of parallel links 6 are pivoted at their lower ends 60 by a pivot pin 14 to the projecting end of each cleat 4. The upper ends of these links are pivoted to a lever 7 by a bolt 9 intermediate the ends of said lever. The lower end of each lever is pivoted by means 65 of a bolt 15 in a bifurcated support 8 attached to the side of the car, and the axis of such pivot is spaced sufficiently from the side of the car so that when the lever 7 70 lies against the car it is beyond dead center and any downward pull by the link 6 tends to firmly bind the lever 7 against the side of the car. For this purpose the lower part of each lever, below the pivot 8 that connects the links 6 is outwardly inclined 75 as clearly shown in Figure 5, so that the upper part of the lever may lie flat against the side of the car.

For holding these levers in their operative position, a latch 10 is pivoted by 80 means of a bolt 16 or the like adjacent the upper end of each lever and is adapted to be swung over the lever, and behind a suitable keeper 11.

In the present instance, I have shown a 85 pair of levers attached to each door. It should however be understood that any number of such levers may be applied to a door, according to the teachings of this invention.

90 The operation of dumping resulting from this invention is as follows:

Assuming that a car is loaded with coal or the like, the levers 7 will be latched to the car as shown in Figure 1. To empty the 100 car, the latches 10 are swung up into inoperative position. The levers 7 are then pulled outwardly by prying with a stick and as soon as the pivots 9 pass beyond dead center, the load on the doors 1 will 105 become effective and swing the latter downwardly upon their pivots until they are held by the links 6 and levers 7 as shown

in Figures 3 and 4. The coal or substance in the car will then pour outwardly in a lateral direction as is obvious.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. In a dump car, a hinged bottom section, cleats extending beyond said section, links pivoted to the ends of said cleats, levers pivoted to the sides of the car and pivoted intermediate their ends to said links, and latches for engaging over said levers when the same are in operative position, the lower ends of said levers being outwardly inclined whereby the pivotal connections thereof with said links normally lie beyond dead center.

2. In a dump car, a hinged bottom sec-

tion, a pair of links connected to said section, a lever pivoted to the side of said car and connected intermediate its ends to said links, a latch for normally holding said lever against the side of the car, the construction being such that the pull of said links upon the lever will normally tend to bind the same against the car.

3. In a dump car, a hinged bottom section, means connected to said section and adapted for embracing the exterior side of the car, and a lever pivoted at its lower end to the exterior side of the car and connected intermediate its ends to said means and means for normally confining said lever against said car.

In testimony whereof I have hereunto 40
subscribed my name in the presence of two
subscribing witnesses.

HOWARD MARTIN.
